United States Patent Office.

HUNNEVILLE VINCENT, OF NEW YORK, ASSIGNOR TO HUGH B. BROWN,
OF BROOKLYN, NEW YORK.

himself and
Letters Patent No. 60,969, dated January 1, 1867.

IMPROVEMENT IN HOOP SKIRTS.

The Schedule referred to in these Letters Patent and making part of the same.

TO ALL WHOM IT MAY CONCERN:

Be it known that I, HUNNEVILLE VINCENT, of New York city, in the county and State of New York, have invented a new and useful Improvement in Hoop Skirts; and I do hereby declare that the following is a full, clear, and exact description of the construction and operation of the same, reference being had to the annexed drawings, making a part of this specification, in which is shown—

Figure 1, elevation of front portion of the skirt with my improvement applied thereto.

Figure 2, perspective view of a hoop, the wire compressing the same crossing itself once in its passage around the skirt.

Figure 3, similar view of a hoop crossing itself twice in its passage around the skirt.

The hoop skirts now in common use have two principal defects; first, their liability to "creep up" or "shorten," caused by the turning of the wires at the pockets which wind the tape around them, and consequently shortens the skirt; second, their liability when pressure is applied from behind, as in sitting down, to rise up in front. Both of the above-mentioned defects are obviated by my improvement, which consists in so arranging the hoops constituting the skirt, that each hoop crosses or intersects itself once or more in its passage around the skirts, whereby and by reason of said crossing of the hoops, their turning over is rendered impossible; and as each hoop acts on every other, any pressure applied on the side of the skirt where the hoops cross or intersect, as in sitting down, exerts a downward movement on the part of the skirt directly opposite.

To enable others skilled in the art to make and use my improvement, I will proceed to describe its construction and operation.

Instead of causing the wires or hoops to run parallel, as in skirts in general use, I so arrange them that each hoop crosses or intersects itself once in front, as shown in fig. 2, and is fastened to the tape in the usual way; or, when required, I cause the hoop to cross or intersect itself twice both in front and back of the skirt, as shown in fig. 3, fastening the ends of the wires to the hoop beneath.

What I claim as my invention, and desire to secure by Letters Patent, is—

The arranging of the wires or hoops in such a manner that each hoop crosses or intersects itself once or more in its passage round the skirt, substantially and for the purposes herein set forth.

HUNNEVILLE VINCENT.

Witnesses:

ASA JOHNSON,

HENRY H. VINCENT.
